US0D1035255S

(12) **United States Design Patent** (10) Patent No.: **US D1,035,255 S**
(45) Date of Patent: ** Jul. 16, 2024

(54) **SHOE**

(71) Applicant: **adidas AG**, Herzogenaurach (DE)

(72) Inventors: **Fionn Corcoran-Tadd**, Portland, OR (US); **Matteo Padovani**, Portland, OR (US); **Robbie Paterson**, Nuremberg (DE); **Falk Bruns**, Nuremberg (DE); **Benjamin Peter**, Herzogenaurach (DE)

(73) Assignee: **adidas AG**, Herzogenaurach (DE)

(**) Term: **15 Years**

(21) Appl. No.: **29/908,960**

(22) Filed: **Jan. 16, 2024**

Related U.S. Application Data

(63) Continuation of application No. 29/831,547, filed on Mar. 21, 2022, now Pat. No. Des. 1,018,005.

(51) **LOC (14) Cl.** **02-04**

(57) **CLAIM**

The ornamental design for a shoe, as shown and described.

DESCRIPTION

FIG. 1 is a top rear perspective view of a shoe showing the claimed design;

FIG. 2 is a top front perspective view thereof;

FIG. 3 is a front elevation view thereof;

FIG. 4 is a rear elevation view thereof;

FIG. 5 is a right side elevation view thereof;

FIG. 6 is a left side elevation view thereof; and,

FIG. 7 is a top plan view thereof.

The broken lines in the figures show portions of the shoe that form no part of the claimed design.

Portions of the shoe that are not shown form no part of the claimed design.

1 Claim, 7 Drawing Sheets
